BROOCH ASSEMBLAGE

Application filed December 1, 1932. Serial No. 645,166.

This invention relates to a brooch which is made up of a back portion to which the pin is attached and an ornate facing made of two parts which are removably clasped to the back portion. Each of the two portions of the facing may be removed and separately used as an ornamental clasp.

The back portion and two clasps which form the facing are assembled in a novel manner by which each clasp is held rigidly in place. There is a hinged clamp on the back of each of the clasps and a spring connecting the clamp with the clasp in such a way as to hold it wide open or draw it closed.

To assemble the brooch these clamps are passed through transverse openings near the center of the back portion and snapped closed. There are three projections on each clamp which fit into separate openings in the back portion. The three projections are designed to fit into the openings in such a way as to hold the clasps in position on the back portion with the minimum amount of play and furthermore the three projections on each clasp are so designed as to hold the clasp rigidly in position when it is used separately from the back portion on a coat lapel or a hat or for other ornamental purposes. Two of the projections are somewhat pointed and inclined toward the hinge of the clasp in such a way as to prevent the removal of the clasp from a dress or coat or other textile material without first opening the clasp. The third projection which is farthest from the hinge is also somewhat pointed, but it is substantially perpendicular and is arranged transversely across the clamp. The side of each clasp toward the hinge is perfectly straight

and these two straight edges are placed adjacent to one another in the assembled brooch. Around the rest of each clasp at the back, i. e. around the outer edges when the brooch is assembled, is a raised rim which projects beyond a shoulder against which the back portion rests when the whole is assembled. The rim thus surrounds the back portion and each clasp is held firmly in place.

The invention will be further described in connection with the accompanying drawing:

Figure 1 shows the brooch assemblage in perspective;

Figure 2 shows the back portion of the brooch with both clasps removed and shows one of the clasps in position to be placed on the back portion;

Figure 3 is a section through the assemblage on line 3—3 of Figure 1;

Figure 4 is a rear view of the assemblage;

Figure 5 shows one of the clasps attached to a piece of cloth; and

Figure 6 shows one of the clasps in the open position.

In the drawing the back portion of the brooch is indicated by the reference numeral 5 and the reference numeral 6 is used to indicate each of the clasps. The front portion is ornamented as desired and may be enamelled or set with jewels or other brilliants. The two clasps placed with their straight edges 7 together cover a somewhat larger area than the area of the back portion and the back of each clasp on all sides except the straight edge 7 is raised to form a rim 8 which fits over the back portion 5 which rests on the shoulder 9, making the entire assemblage perfectly rigid. The clamp 10 of each clasp is connected with the ornamented face 11 by a spring 12. The spring is fastened at one end to the clamp at 13 and at the other to a suitable hook or eye 14 which is closer to the ornamented face than the hinge 15 and between the hinge and the straight edge 7 so that when the clasp is opened the spring holds it open and when it is closed, the spring holds it closed.

There are two projections 20 at each side of each clamp and a third projection 21 toward the end of the clamp. These fit into the openings 22 and 23 in the back portion 20 of the brooch. The projections 20 are inclined toward the middle of the brooch. The projection 21 is ordinarily perpendicular. The effect of the three projections when a clasp is snapped on to a hat, coat or dress, etc., is to hold the clasp firmly against the cloth, etc. and prevent its removal except by opening the clamp.

In assembling the brooch the clamp 10 of each clasp is opened as shown in Figure 100

2 and the clamps are passed through the transverse openings 25 and 26, and then they are snapped closed so that the projections 20 and 21 coincide with the openings 22 and 23. These two transverse openings are connected by an opening 27 to provide space for the springs when the clamps are open. Further openings 28 and 29 connecting with the transverse openings provides space for the springs when the brooch is assembled and the clamps closed.

I claim:

- 15 1. A brooch assemblage which comprises a back portion and two ornamental clasps, one edge of each clasp being a straight edge and to each clasp adjacent the straight edge being hinged a clamp on which are three projections, one of the projections being at the end, the other two being intermediate between this end and the hinge with their outer ends inclined somewhat toward the hinge, the back side of each of the clasps on all sides except the straight edge being raised to form a rim adapted to fit tightly over the back portion of the brooch and being formed with a shoulder just under the rim against which the back portion rests, the back portion to which the clasps are fastened comprising six openings adapted to receive the three projections on the clamp of each clasp and transverse openings through which the clamps pass, the clamp of each clasp being connected by a spring with the ornamented face at a point between the hinge and straight edge and nearer the face than the hinge, an opening being provided in the back portion connecting said transverse openings to provide space for said springs when the clamps are open and openings to provide space for said springs when the clamps are closed.
- 20 2. A brooch assemblage comprising a back member and at least one ornamental clasp removably secured thereto, a rim provided with an inner shoulder extending at least a part of the way around the edge of one of said members, the other member being seated on said shoulder, and means for removably retaining the back member and the clasp in assembled position.
- 25 3. A brooch assemblage comprising a back member and at least one ornamental clasp secured thereto, a rim provided with an inner shoulder extending at least a part of the way around the edge of one of said members, the other member being seated on said shoulder, and a clamp hingedly connected to the clasp for removably retaining the clasp and the back member in assembled position.

60

4. A brooch assemblage comprising a back member having apertures therein and at least one ornamental clasp secured thereto, a rim provided with an inner shoulder extending at least a part of the way around the edge of the clasp, the back member being seated on said shoulder, and a clamp hingedly connected to the clasp for removably retaining the back member in position on said shoulder, said clamp having projections which, when the clamp is in closed position, extend into the apertures in the back member.

5. A brooch assemblage comprising a back member and at least one ornamental clasp, a clamp hingedly secured to the clasp for removably securing the clasp to the back member, and an extensible spring connecting the clamp at a mid-point to the clasp for holding the clamp either in open or closed position.

6. A brooch assemblage comprising a back member and at least one ornamental clasp, a clamp hingedly secured to the clasp for removably securing the clasp to the back member, and an extensible spring connecting the clamp at a mid-point to the clasp for holding the clamp either in open or closed position, the back member being provided with an opening into which the spring is received when the clamp is in closed position.

7. A brooch assemblage comprising a back member having a fastener for securing the same to clothing or the like, two ornamental clasps, a rim provided with an inner shoulder extending a part of the way around the edge of each clasp, the back member being seated on said shoulders and within said rim, a clamp hingedly carried by each of said clasps and having means for engaging the back member to removably secure the clasps to the back member.

8. A brooch assemblage comprising a back member having a fastener for securing the same to clothing or the like, two ornamental clasps, a rim provided with an inner shoulder extending a part of the way around the edge of each clasp, the back member being seated on said shoulders and within said rim, a clamp hingedly carried by each of said clasps and having means for engaging the back member to removably secure the clasps to the back member, and a spring connecting each clamp to its respective clasp for holding the clamp either in open or closed position.

In testimony whereof I affix my signature.

OSCAR PLACCO.
